UNITED STATES PATENT OFFICE.

ROSCOE BEAN, OF SPRINGFIELD, OHIO, ASSIGNOR TO THE MAST, FOOS & COMPANY, OF SAME PLACE.

PUMP.

SPECIFICATION forming part of Letters Patent No. 429,411, dated June 3, 1890.

Application filed November 14, 1887. Serial No. 255,044. (No model.)

To all whom it may concern:

Be it known that I, ROSCOE BEAN, a citizen of the United States, residing at Springfield, in the county of Clark and State of Ohio, have invented certain new and useful 5 Improvements in Pumps, of which the following is a specification, reference being had therein to the accompanying drawings.

This invention relates to certain new and 10 useful improvements in double-acting force-pumps, the peculiarities of which will hereinafter be more fully described, and pointed out in the claim.

In the accompanying drawings, forming a 15 part of this specification, and on which like reference-letters indicate corresponding parts, Figure 1 represents a vertical sectional view of my improved pump, showing some of the parts in side elevation; Fig. 2, a vertical sectional view of the pipe-cap, the water-pipe, the coupling, and the cylinders, and a side elevation of the several other parts thereof, omitting the divided head and handle; Fig. 20 3, a vertical sectional view of a portion of the water-pipe and the cylinder and of the coupling, showing a modification in the construction thereof; Fig. 4, a horizontal section 25 on the line $y-y$ of Fig. 3, looking in the direction of the arrow, of the coupling detached; Fig. 5, a horizontal sectional view of the divided head and pipe-cap on the line $x-x$ of Fig. 1, looking in the direction of the arrow; Fig. 6, a detail side elevation of the coupling with a portion of the outer cylinder in section; 30 and Fig. 7, a partial section and elevation of the several pipes, showing a modified form of the cap.

The letter A designates a platform or well-curb of any approved construction, upon 40 which is mounted the two-part vertically-divided head B, one half of which is removed in Fig. 1, so as to show the interior arrangement of the parts. A standard C extends from each of the halves, and together forms a support of the handle D, while the lower 45 ends of said halves are enlarged to form a casing E, as clearly seen in Fig. 1. Within this casing is suspended a hollow pipe-cap F, consisting of a metallic vessel of suitable

dimensions to receive the quantity of water 50 raised by the pump, and of such shape as to conveniently occupy the interior of the casing E, as seen more clearly in Fig. 5. A tubular air-chamber G and a discharge-pipe H, having a spout I, are connected with the pipe-cap F and clamped and held by the two halves of the head B between their meeting edges. So far as concerns the divided head, *per se*, I wish to be understood that such is not new. Thus the pipe-cap is sustained within the casing E, and thus a means of connection is established between the discharge-pipe and the water-pipe which delivers the water from the cylinders upward, as also a means of communication between the 65 air-chamber and the uprising volume of water, whereby an even stream is produced.

A pipe J is connected with the pipe-cap and with the coupling K, and forms the essential means by which the lower mechanism 70 of the pump is suspended, as also the water-pipe which delivers the water to the hollow pipe-cap. Within the pipe, and extending from the coupling K into and through the pipe-cap, is a tubular piston-rod casing L, 75 whose essential function is that of avoiding the necessity of a packing-box between the piston-rod and the coupling and between that rod and the said cap. This tubular casing L is connected with the coupling and the pipe-cap either by being screwed into threaded 80 apertures therein or by being merely passed through smooth apertures and provided with a nut, as seen in Figs. 1 and 2.

The coupling K consists of two segmental 85 parts M and an upper cylindrical sleeve N and a lower cylindrical sleeve O, to the former of which the pipe J connects and to the latter of which the outer cylinder connects, as by screw-threads. Water passages or ports P extend through the diaphragm or horizontal wall Q (see Fig. 4) of the coupling, and serve to form communication between the cylinders and the interior of the segmental parts M. The wall Q forms a part of the 90 shell-like structure of the coupling and occupies the area not occupied by the lower ends of the segmental parts M, and consti- 95

tutes a part in which an opening is formed for the reception of the sub-coupling R, by which the inner cylinder is suspended from the coupling K and within the outer cylinder.

5 The sub-coupling is of two forms, that shown in Fig. 3 consisting of a tube S and a plug T, screwed together and respectively into said opening and into the inner cylinder. In the form shown in Fig. 2 the tubular and plug-like portions are formed in one piece, being by preference a casting. In this form the tube-like portion is also of greater diameter than in the form shown in Fig. 3. I prefer that shown in Fig. 3.

15 The letters U and V designate, respectively, the outer and inner cylinders, which are so proportioned, relatively, that about one half of the water lifted by the upstroke of the pistons passes into the inner cylinder and the remaining half between the cylinders, whereby on the downstroke of the pistons about the same quantity of the water is forced up as is lifted on the upstroke thereof, the result being a perfectly-uniform delivery of water at 25 the spout.

The piston-rod is designated at W, and is provided with a lift-piston X and a force-piston Y of the usual or any approved construction. The rod itself is preferably of tubular form, as 30 seen in Fig. 2, and is provided with an opening a below the force-piston for the purpose of constituting an air-chamber to prevent or avoid any tendency to "pounding." The outer cylinder at its lower end is provided 35 with its usual check-valve b and a lift-pipe c. It will be observed that the inner cylinder terminates below the flange O of the coupling, whereby the comparatively small space at this point is not unduly occupied by the 40 parts, thus leaving ample space for the unobstructed passage of the water. Again, the ports P, being of the form shown in Fig. 4—that is, segmental—also allow ample freedom. It will also be observed that the pipe J, being 45 sufficiently large, gives ample passage for the water, notwithstanding the tubular casing L, and is also large enough to strongly sustain the lower mechanism of the pump and prevent the same from any tendency to sway or 50 rock laterally. Again, the exterior of the pump is smooth or symmetrical, is devoid of projections, and is all within the outer diameter, or does not exceed that diameter, of the cylinder U, whereby the pump is excellently 55 adapted to the purposes of the bored wells, sometimes known by the name of "deep wells," by reason of the great depth to which some bored wells are extended. The pipe J is made longer or shorter according to the 60 depth of the well, being in pumps intended for deep wells sufficiently long to bring the check-valve b from twenty-four to twenty-six feet above the surface of the water-supply. The divided head constituting a strong and

firm support for the pipe-cap F through the medium of the air-chamber and discharge-pipe, the said cap thereby becomes a stanch connection for the proper sustaining of the pipe J. It will be noted that any water remaining in the hollow pipe-cap after operating the pump immediately flows back into the lower part of the pump, and is thus prevented from freezing.

The diameter of the tubular air-chamber G may be varied to suit the work the pump is to do, though it is shown in the present instance as about the same diameter as the discharge-pipe H. The length of said chamber may also vary.

In Fig. 7 I have shown the water-pipe J connected to the discharge-pipe and the air-chamber by a different form of cap from that shown in the other figures, the difference being that the cap shown in Fig. 7 is not hollow, as in the other figures. The essential functions of the hollow cap are subserved, however, by the cap F', for I have spoken of the cap F as forming a connection between the discharge-pipe and the pipe which delivers the water from the cylinders as forming a means for communication between the air-chamber and the uprising volume of water, and as forming a stanch connection for sustaining the pipe J through the medium of the air-chamber and discharge-pipe, and these things are accomplished by the cap F'. The cap F' is also so located as to be inclosed by the casing E of the divided head in the same manner that the cap F is inclosed. Thus the two forms of caps are in all essential details particularly the equivalents of each other. The attachment of the piston-rod casing to the cap F' is also the same as its attachment to the cap F.

It is desirable that the portion of the water-pipe which serves as a support to the cylinders should be comparatively large to afford strength and to prevent the cylinders from swaying, while it is equally desirable that this larger size should terminate about where it is secured at the platform end, and the remainder of the pipe, or that portion called the "discharge-pipe," be reduced to a smaller size, so as to avoid lifting so much water before securing a flow at the spout, and also to avoid so great an accumulation of water, which, after using the pump, has to flow back below to prevent freezing.

The cap, either form, is used as a means of connecting these two sizes of the water-pipes, and also affords a cover or supporting portion of said pipe.

The diameter and the depth of the hollow form of cap may be varied to suit particular circumstances.

Having thus fully described my invention, what I claim as new, and desire to secure by Letters Patent, is—

In a pump, the combination of a coupling, the body or intermediate portion of which is composed of hollow segmental pipe-like parts separated by a lateral opening or space between them, of an upper annular hollow body or shell, and of a lower annular flange, and a tubular piston-rod casing projected through said upper body of the coupling and into said

opening, and provided with a nut or other fastening accessible through said opening. ¹⁰

In testimony whereof I affix my signature in presence of two witnesses.

ROSCOE BEAN.
